PICKER CONTROL FOR LABEL-APPLYING MACHINES

Sidney T. Carter, Worcester, Mass., assignor, by
mesne assignments, to Geo. J. Meyer Manufac-
turing Company, Cudahy, Wis., a corporation
of Wisconsin

Application June 28, 1950, Serial No. 170,763

9 Claims. (Cl. 216—54)

1

This invention relates to labeling machines and in particular to a machine of the kind disclosed in my Patent 2,528,944 for "Picker Control for Label-Applying Machines," granted November 7, 1950.

In that machine a two-part picker oscillated through a path of predetermined length and had applied thereto at one point in its path during each oscillation a coating of adhesive. Following application of the adhesive the picker moved into contact with a label at one extremity of its movement, which adhered to the freshly coated portion thereof whereupon the picker moved to the opposite extremity of its path of movement and came to rest with the label substantially parallel to but spaced from the surface of the article to which it was to be applied and with its adhesive coated surface facing the article. Thereupon a transfer member oscillatable from an inoperative position to a label-applying position moved into contact with the uncoated side of the label supported by the picker, the picker parts moved laterally in the plane of the label now held by the transfer member and in doing so spread the adhesive on the coated surface and having cleared the transfer member the latter moved on between the separated parts and beyond them into label-applying position where it applied the adhesive-coated side of the label to the article. The separated picker parts were then restored to their contiguous positions and the picker returned to the opposite end of its path of movement for another coating of adhesive and another label. In that machine a detector was provided which was operable in the absence of an article to which a label was to be applied to shorten the stroke of the picker at the label end of its movement so that it could not reach the labels and hence would not pick off another label. This however, left the coated surface of the picker exposed so that as the picker and transfer member went through their normal movements the transfer member came into contact with the adhesive coated surface of the picker and acquired a coating of adhesive. To prevent this, other means was provided which was effective in the absence of an article, and hence a label on its surface, to lengthen the movement of the picker so that it moved beyond the extreme label-applying position of the transfer and hence to prevent the latter from ever coming in contact with its coated surface. A disadvantage in the foregoing structure however, became apparent when an adhesive was used which was tacky due to the formation of strings drawn out between the separated parts of the picker which

2

were then applied to the surface of the transfer member as the picker parts passed by it in their rearward return movement. The principal object of the present invention is to provide an improved structure embodying substantially the same operating elements as the prior machine, constructed and arranged by a relocation of the parts and somewhat different timing of their movement to avoid the application of adhesive to the surface of the transfer member in the absence of a label on the picker. To this end and as illustrated herein the picker is relocated so that it has an extreme forward transfer position short of the article to be labeled, so that the transfer member moves into contact with the picker to take a label therefrom in normal operation when there is an article present for application of a label thereto, and then continues on beyond the transfer position to apply the label to the article, but which is limited in its return stroke, by the absence of an article, to some intermediate position between the label-applying position and the transfer position so that the picker idles harmlessly between the transfer member and the label-picking position. The transfer member is held fixed at this intermediate position so long as no article is present at a position to be moved to the label-applying position. Simultaneously other means shortens the stroke of the picker at the label-picking end of the stroke so that it never reaches label-receiving position and hence does not accumulate a quantity of labels.

The invention will now be described in greater detail with reference to the accompanying drawings, wherein:

Fig. 1 is a side elevation of the machine partly in section showing the label transfer member held in its inoperative position in the absence of an article to be labeled;

Fig. 2 is a fragmentary portion of the machine in elevation to larger scale showing the feeler-operated mechanism for holding the label transfer member in its intermediate position;

Fig. 3 is a plan view of the transfer member operating cam; and

Fig. 4 is a plan view of the machine as seen from the top showing the feeler mechanism and omitting the picker and transfer member.

Referring to the drawings, Fig. 1, the machine comprises essentially a substantially horizontal track 10 along which articles are moved successively to a label-applying position S1 for labeling, a label picker 12 arranged to oscillate between a source 14 of labels L and a label transfer position to supply labels to a transfer member 16 which

in turn is arranged to oscillate to and from label-applying position and in its movement toward label-applying position to pass through the transfer position, take a label from the picker and carry it forward to label-applying position for application to the article which rests on the track 10 at label-applying position. The foregoing operating instrumentalities are mounted for movement in proper sequence between spaced uprights 20-20 on a base plate 18 held at a suitable height from the floor by legs, not shown. The base plate also provides support for the track 10 and backing for the article resting thereon during application of the label to the article.

In the machine disclosed in my Patent 2,528,944 the picker and transfer element are mounted to swing in an arcuate path on substantially vertically spaced parallel shafts mounted between the uprights close to the label-applying position. As thus arranged the picker at the forward extremity of its movement under normal conditions extends nearly vertically downward with respect to its axis of oscillation. The transfer element makes contact with the picker at that place in a nearly vertical position and then moves forwardly to apply the label to the article. As illustrated therein, when no article was present for movement to label-applying position, as the transfer element moved toward transfer position for contact with the picker the latter moved beyond its normal position and out of reach of the transfer element, this being effected by feeler controlled mechanism. The difficulty with that construction was that the picker included two parts which separated at transfer position to disengage the label and leave it on the transfer element. Hence in the absence of a label the adhesive on the picker parts, because of its tacky nature, stretched out between the parts in long strings and when the picker moved rearwardly past the transfer member these strings of adhesive clinging to the separated parts of the picker were laid across the face of the transfer element. To avoid this in the instant machine the parts are so arranged that the picker never moves beyond the transfer position and the transfer element is held in a position between label-applying position and the extremity of forward movement of the picker so that it cannot return to its initial back position for the next forward movement, with respect to the picker, until there is an article ready to be moved into label-applying position. As illustrated the picker shaft 24 is journaled in a horizontal position between the uprights 20-20 rearwardly of the article support 10 substantially midway between it and the label supply 14 so that it swings approximately the same arcuate distance at each side of the vertical through its axis. The picker 12 which, like that shown in the pending application, has two parts which are separable at transfer position to permit the transfer element to take the label therefrom, is hung on a sleeve 28 splined or otherwise fixed to the shaft 24 and from the sleeve there projects upwardly an arm 30 having a rearwardly facing flat 32. An arm 34 is also mounted on the shaft 24 but is free to turn thereon and has a forwardly facing flat 35 normally held in engagement with the flat 32 by a stiff spring 36 connected between the arms so that the arms 30 and 34 together form a crank for effecting oscillation of the picker 12. To this end the extremity of the arm 34 is connected to the upper end of a link 38 the lower end of which is connected to the upper end of a

shackle 40. The lower end of the link 38 and the upper end of the shackle 40 each have a flat 42 which are arranged to be held in abutting relation by a second spring 44 extending between an arm 46 extending laterally from the link 38 and an arm 48 extending laterally from the shackle 40. The spring 44 is stiff enough normally to hold the link 38 and the shackle 40 in straight-line relation so that motion imparted to the shackle 40 will normally impart oscillation through the arm 34 to the shaft 24 and hence oscillation to the picker 26. A driving rod 50 is connected at its upper end to the lower end of the shackle 40 and extends downwardly below the base plate 18 where its lower end is connected to means for effecting substantially vertical reciprocation thereto. Normally, that is when the link 38 and shackle 40 are in straight-line relation, reciprocation of the rod 50 will cause oscillation of the picker 26 from a place of contact with the exposed label L in the label magazine 14 to the label transfer position shown in dotted lines near the article support. A short arm 52 is formed integral with and projects forwardly from the upper end of the link 38 and has connected to its free end the upper end of a latch rod 54 which has at its lower end a latch 56. If uninterfered with, the latch 56 will reciprocate vertically with the oscillation of the arm 34. However if the latch is engaged so that the rod 54 cannot move upwardly, the vertical upward movement of the rod 50 will break the straight-line position between the link 38 and shackle 40 so that the shaft 24 will be turned a lesser amount during counterclockwise rotation, hence the picker 12 will stop short of the label magazine at the position shown in full lines so as not to have contact with a label in the magazine. A shortening of the angular rotation of the shaft 24 of approximately 15° is sufficient. The break in the drive through arms 30 and 34 prevents damage to the parts in the event the picker is stopped at some point short of its forward movement by a foreign object interjected in its path.

During each oscillation of the picker a coating of adhesive will be applied to its surface by means of a glue applying roll 60. As illustrated the roll 60 is mounted at the lower end of an arm 62, the upper end of which is pivotally supported on a horizontal shaft 64 journaled between the uprights 20-20 and there is means not shown for oscillating the arm 62 in timed relation with the oscillation of the picker 26 so as to cause the roll 60 to have rolling contact with the label-receiving surface of the picker, as the latter is returning to label-receiving position, thereby to apply a coating of adhesive thereto. The roll 60 is supplied with adhesive from a partially submerged pick-up roll 66 journaled for rotation in a receptacle 68 mounted on the base plate 18. The details of the construction and of operation of the glue applying roll are described in my pending application and there is no need for further explanation herein.

The transfer member 16 comprises an arm 70 bolted at its lower end to a casting 72 the latter being fixed to a horizontal shaft 74 journaled at its ends between the uprights 20-20 close to the label-applying position forwardly of the shaft 24 so that when it is in a substantially vertical position it is situated beyond the extremity of the movement of the picker. The upper end of the arm 70 carries a transfer pad 82 pivotally connected thereto at 84 and has connected thereto a flexible vacuum hose 86. A limit arm 88 pro-

jects upwardly from the transfer pad and has in it an adjustable screw 90 for engagement with a fixed stop 92 to limit the forward movement of the arm 88 towards the article to be labeled. Oscillation of the transfer member 16 is effected by an arm 76 (Fig. 4) fixed to an end of the shaft 14 which has on it a cam follower 120 arranged to have contact with the edge of a cam disc 116 (Figs. 3 and 4) mounted on a horizontal cam shaft 118. The cam disc 116 is so shaped that it moves the transfer member from its inoperative position to transfer position and into contact with the label at that point, pauses while suction is established at the face of the transfer pad by way of a hose 86 so as to take the label from the picker when the picker parts separate and then moves on to the article in label-applying position S1. Return movement of the transfer member is effected by a spring 122 connected to an arm 80 extending downwardly from the arm 76.

In the normal operation of the machine as long as articles are successively advanced to label-applying position S1 on the track opposite the transfer member, the picker 12 oscillates from label-receiving position to transfer position whereupon the transfer member moves from its inoperative position to transfer position, takes a label from the picker at the transfer position, and continues to label-applying position where it applies the label to the article.

As in the prior machine a feeler is provided for determining whether there will be an article at label-applying position when the transfer member moves to applying position and this feeler is arranged to control the movement of the picker so that the latter will not take a label from the label magazine in the absence of an article at the label-applying position. Since the picker, however, receives an application of adhesive regardless of whether it takes a label from the label magazine or not, it is necessary to control the movement of the transfer member with reference to the picker so that there is no chance for the former to receive adhesive on its label-carrying surface. To this end, in contradiction to the prior machine in which the picker stroke was increased so that it moved ahead of the transfer element, the forward extremity of the path of movement of the picker is not changed but instead the transfer member 16 is prevented from returning to its initial back position for another forward motion with respect to the picker, that is, it is held between label-applying position and transfer position while the picker oscillates idly so long as there is no article at station S2. Referring to Fig. 4, the feeler 94 is arranged close to the track on which the articles rest for movement from a ready or feeler position S2 toward label-applying position S1. The feeler 94 is fastened to one end of an arm 96, the latter being fixed to one end of a vertical shaft 98 journaled in a vertical bearing 100. The shaft 98 has an angle arm 101 from which extends a tail 102 the rear end of which terminates between a pair of spaced pins 104 (Fig. 4) fixed to the upper side of a horizontal bar 106. The bar is arranged to slide between guide block 108 and 110 (Fig. 2) and has extending laterally from its under side a block 112 (Fig. 4). An arm 78 is fastened to the shaft 14 for oscillation therewith and is so arranged with reference to the bar 106 that in one position of the bar 106 the block 112 will intercept the movement of the arm 78 and hold the transfer member 16 in fixed vertical posi-

tion. As thus constructed, if there is an article on the support in the ready position S2 to be moved into label-applying position S1 the feeler 94 will be held deflected away from the track against the normal tension of the spring 114 so that its rear end draws the bar 106 toward the left as seen in Fig. 2. In this position the block 112 is situated to the left of the arm 78 so that oscillation of the arm 70 which carries the transfer pad 82 takes place without interference. The cam 116 on the shaft 118 turns constantly and effects positive forward movement of the arm 70 to bring the transfer pad into label-applying position. Normally the transfer pad is returned to its inoperative position by the spring 122. If there is no article on the track in readiness for movement to label-applying position the feeler 94 is pulled inwardly to a position substantially parallel to the track by the operation of the spring 114 which at the same time pulls the tail 102 counterclockwise with respect to the pivot 98 and thus urges the bar 106 toward the right. Until the transfer pad 82 moves up to label-applying position the block 112 merely rests against the arcuate surface 124 of the arm 78 under the yielding pull created by the spring 114. When the transfer member 70 moves to label-applying position, however, the arm 78 moves downwardly far enough to permit the block 112 to slide by its upper end into the position shown in Fig. 1. Hence, when the transfer arm 70 starts to return to its inoperative position under the influence of the spring 122, the arm 78 will come in contact with the block 112 and the arm 70 will be held substantially vertical as shown in Fig. 1, midway between label-applying position and label transfer position. Until an article is present on the track at position S2 in readiness for movement to label-applying position S1 the transfer pad 82 will remain at this mid-position so the picker never reaches it.

At the same time an end of the bar 106 engages the latch 56, the lower end of which is held between guide blocks 126 (Fig. 1) and holds the rod 54 in a depressed position. This, as heretofore pointed out, breaks the straight-line drive between the link 38 and shackle 40, thereby shortening the angle of rotation of the shaft 24 so that the picker will not reach the labels in the label magazine 14. As a result the picker 26 oscillates between the transfer member and the label magazine without reaching either one, so that labels are not picked up by it, nor can adhesive be applied to the face of the transfer pad.

It should be understood that the present disclosure is for the purpose of illustration only and that this invention includes all modifications and equivalents which fall within the scope of the appended claims.

I claim:

1. In a labeling machine a picker, means for oscillating the picker continuously through a path of predetermined length from a label-receiving position at one extremity of its movement to a label transfer position at the other extremity of its movement, a label transfer element, means for effecting movement of said transfer element to and from a label-applying position through said label transfer position in timed relation to the oscillation of said picker to take the label from the picker at said transfer position and carry it forward to the label-applying position, a detector responsive to the presence or absence of an article at a place for

movement to label-applying position, and means controlled by the detector in the absence of an article at said detecting position to intercept the transfer element as it moves away from label-applying position and hold it at a place intermediate the label-applying position and said transfer position.

2. In a labeling machine, a picker, means for oscillating the picker continuously through a path of predetermined length from a label-receiving position at one extremity of its movement to a label transfer position at the other extremity of its movement, a label transfer element, means for effecting movement of said transfer element to and from the label-applying position through said label transfer position, in timed relation to the oscillation of said picker to take the label from the picker at said transfer position and carry it forward to label-applying position, a detector responsive to the presence or absence of an article at a place for movement to label-applying position, a holding arm associated with the transfer element and movable therewith, and a stop movable from an inoperative position to a position in the path of movement of the holding arm to intercept it and to hold the transfer element at a place intermediate the label-applying position and said transfer position, movement of said stop into operative position being effected by the response of the detector to the absence of an article at detecting position.

3. In a labeling machine, a picker, means for oscillating the picker continuously through a path of predetermined length from a label-receiving position at one extremity of its movement to a label transfer position at the other extremity of its movement, a label transfer element, means for effecting movement of said transfer element to and from a label-applying position through said label transfer position in timed relation to the oscillation of said picker to take the label from the picker at said transfer position and carry it forward to label-applying position, a holding arm associated with the transfer element, a stop movable from an inoperative position to a position in the path of movement of the holding arm to intercept the arm and hold the transfer element at a place intermediate the label-applying and transfer positions, and a detector operable in the absence of an article at detecting position to shift the stop from inoperative to operative positions.

4. In a labeling machine, a picker, means for oscillating the picker continuously through a path of predetermined length from a label-receiving position at one extremity of its movement to a label transfer position at the other extremity of its movement, a label transfer element, means for effecting movement of the transfer element to and from a label-applying position through said label transfer position in timed relation to the oscillation of said picker to take the label from the picker at said transfer position and carry it forward to the label-applying position, and means for intercepting and holding the transfer element in a position intermediate the label-applying position and the transfer position in the absence of an article at a ready position for movement to the label-applying position, said means including a stop movable into the path of a portion of the transfer member to intercept it and hold it in said intermediate position, a detector lever arranged with one end at said ready position for move-

ment to label-applying position and the other end connected to said stop, said lever being pivoted between its ends and means yieldably urging the lever in a direction to move the stop into operative position, said lever being held inoperative against said yieldable means by contact of the lever with an article at said ready position for movement to label-applying position.

5. In a labeling machine, a picker, means for oscillating the picker continuously through a path of predetermined length from a label-receiving position at one extremity of its movement to a label transfer position at the other extremity of its movement, said means including an articulated element the parts of which are normally held in straight line position, a latch bar arranged normally to oscillate with the articulated element said latch bar being operable to break the articulated element so as to shorten the oscillation of the picker, a label transfer element, means for effecting movement of said transfer element to and from a label-applying position through said label transfer position in timed relation to the oscillation of said picker to take a label from the picker at said transfer position and carry it forward to label-applying position, a detector responsive to the presence or absence of an article at a place for movement to label-applying position, and means controlled by the detector in the absence of an article concomitantly to interrupt and stop the transfer element as it moves away from label-applying position at a place intermediate the label-applying position and the transfer position and to intercept the latch bar and hence to break the articulated element on the return movement of the picker toward label-receiving position to prevent the picker from reaching label-receiving position.

6. In a labeling machine, a picker, means for oscillating the picker continuously through a path of predetermined length from a label-applying position at one extremity of its movement to a label transfer position at the other extremity of its movement, said means including an articulated element the parts of which are normally held in straight line position, a latch bar arranged normally to oscillate with the articulated element said latch bar being operable to break said element so as to shorten the oscillation of the picker, a label transfer element, means for effecting movement of said transfer element to and from label-applying position through said label transfer position in timed relation with the oscillation of said picker to take the label from the picker at said transfer position and carry it forward to label-applying position, a detector responsive to the presence or absence of an article at a place for movement to label-applying position, and means controlled by the detector in the absence of an article to intercept and stop the transfer element as it moves away from label-applying position at a place intermediate the label-applying position and the transfer position and concomitantly to intercept the latch bar and hence to shorten the path of return movement of the picker toward label-receiving position so that the picker does not reach the labels.

7. In a labeling machine a transfer element movable through a predetermined path from an inoperative position to a label-applying position, means for effecting movement of the transfer element along said path, a picker, means for effecting movement of the picker with a label adhered thereto to a point of label transfer in said path of movement of said transfer element

in timed relation so as to precede the arrival of the transfer element at that point, means carried by the transfer element for removing the label from the picker at said point of transfer before said element moves toward said label-applying position, and means for bringing the transfer element to rest during its return movement between its label-applying position and said point of transfer, in the absence of an article to succeed the article from which the transfer element is receding.

8. In a labeling machine a transfer element movable through a predetermined path from an inoperative position to a label-applying position, means for effecting movement of the transfer element along said path, a picker, means for effecting movement of the picker with a label adhered thereto to a point of label transfer in said path of movement of said transfer element ahead of said transfer element, means carried by the transfer element for removing the label from the picker at said point of transfer before said element moves toward said label-applying position, a detector responsive to the presence or absence of an article for movement to label-applying position and means controlled by the detector in the absence of an article at said detecting position to bring the transfer element to rest during its return movement between the label-applying position and the point of label transfer from the picker to the transfer element.

9. In a labeling machine, a picker, means for oscillating the picker continuously through a path of predetermined length from a label-applying position at one extremity of its movement to a label transfer position at the other extremity of its movement, said means including articulated

elements the parts of which are normally yieldably held in a straight line position, a latch bar arranged normally to oscillate with one of the articulated elements said latch bar being operable to break said element so as to shorten the oscillation of the picker in one direction of its movement, a label transfer element, means for effecting movement of said transfer element to and from label-applying position through said label transfer position in timed relation with the oscillation of said picker to take the label from the picker at said transfer position and carry it forward to label-applying position, a detector responsive to the presence or absence of an article at a place for movement to label-applying position, and means controlled by the detector in the absence of an article to intercept and stop the transfer element as it moves away from the label-applying position at a place intermediate the label-applying position and the transfer position and concomitantly to intercept the latch bar and hence to shorten the path of return movement of the picker toward label-receiving position so that the picker does not reach the labels, said other articulated member being adapted to break upon interposition of an immovable object in the path of the picker during movement thereof toward transfer position.
